(57) CLAIM

The ornamental design for a purse, as shown and described.

DESCRIPTION

FIG. 1 is a top, front, right perspective view of the claimed design for a purse;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a top, front, right perspective view of the claimed design in an alternative configuration.

In the drawing, the sets of parallel lines indicate surface shading. The broken lines immediately adjacent to the shaded area depict boundaries of the claimed design and form no part thereof. The broken lines showing the remainder of the purse depict environmental structure and form no part of the claimed design. The unshaded regions within the claimed region that broken lines demarcate form no part of the claimed design.
